UNITED STATES PATENT OFFICE

JOHN VAN BRUNT, OF FLUSHING, NEW YORK, ASSIGNOR TO INTERNATIONAL COMBUSTION ENGINEERING CORPORATION, OF NEW YORK, N. Y., A CORPORATION OF DELAWARE

APPARATUS FOR GENERATING STEAM BY THE BURNING OF FUEL IN SUSPENSION

Application filed March 27, 1926. Serial No. 97,873.

This invention relates to generation of steam, and is particularly useful where the fuel is to be burned in suspension, as is the case, for example, with pulverized coal.

5 The nature of the invention and its objects will be best understood from the following brief statement.

There are a number of different forms of standard boilers now very largely used, but 10 the development of the power requirements has been so rapid that standard forms of boilers are incapable of generating the steam required, that is to say, they are incapable of developing the capacities needed to meet 15 modern power requirements.

There are many such standard boiler installations now in existence, and it is one of the primary objects of my invention to convert these existing boilers into high capacity 20 boilers in a simple and effective manner.

The invention is also useful in the making of new installations where it is desirable to employ, in combination therewith, standard boilers or material parts of standard boiler 25 constructions.

How the foregoing, together with such other objects as may hereinafter appear, or are incident to my invention, are realized, is illustrated in the accompanying drawings, 30 wherein—

Fig. 1 is a vertical section through a Ladd type of boiler equipped with my improvements.

Fig. 2 is a similar cross section illustrating 35 the application of my improvements to a horizontal tubular boiler.

Fig. 3 is a similar view illustrating the application of my improvements to an inclined tubular boiler, such as a Sterling boiler.

40 Fig. 4 is a section illustrating the application of my improvements to a boiler of the cross drum type.

Referring now to Fig. 1, the reference character A in general denotes a Ladd boiler 45 with its refractory setting. In the main this boiler comprises an upper drum 7, a lower drum 8, and a bank of connecting tubes 9, such tubes being suitably baffled to provide any desired number of passes.

50 In applying my invention to such a boiler

installation I rip out that portion of the setting in front of the boiler and substitute therefor a combustion chamber indicated, as a whole, by the reference B, this combustion chamber being set in front of the boiler in 55 such manner that that part of the space in front of the boiler which constituted a portion of the original combustion chamber becomes the off-take of the installation, in consequence of which the original boiler becomes, in effect, an economizer section or sections located in such off-take.

To be more specific the combustion chamber B is composed of tubular boiler elements arranged in the shape of a furnace. This 65 combustion chamber includes the front and rear tubular water walls 10 and 11, which walls are preferably composed of tubes having longitudinal fins 12; the side water walls 13 composed of similarly finned tubes; the 70 top tubular water wall 14; the tubular screen 15 to be more particularly described, and the headers 16 and 17, and the drums 18 and 19.

The tubes of the water wall 10 are connected at their lower ends into the drum 19, and at their upper ends into the header 16. The tubes of the rear water wall 11, have their lower ends connected into the header 17 and their upper ends connected into the 75 drum 18; the tubes of the side walls have 80 their lower ends connected into the headers 20 and their upper ends connected into the headers 21. The headers 20 are connected at one end into the drum 19, and the headers 21 are connected at their opposite ends into 85 the drum 18. The tubes of the top wall 14 are connected at one end into the header 16 and at the other end into the drum 18. The tubes of the water screen 15 have one end 90 connected into the drum 19 and the other end into the header 17. The top wall and the water screen are inclined as shown, and the drum 19 is supplied from the drum 8 by a suitable pipe or pipes 22, whereby circulation takes place from the drum 19 upwardly 95 through all of the tubes described, circulation with the standard boiler being completed by virtue of the connecting pipes 23 which lead from the drum 18 to the upper

100 drum 7.

The tubes of the screen 15 are spaced rather widely apart and constitute the outlet from the combustion chamber formed by the furnace-shaped boiler, below which outlet is the 5 ash pit 24 communicating at the rear with the off-take 25 from the furnace previously generally described.

The powdered coal is admitted preferably by burner means located at the upper corners 10 of the furnace shaped boiler diagrammatically indicated at 26. The pulverized coal preferably with preheated air for combustion, is admitted through and at the burners, producing a violently swirling vertical type 15 of combustion, with consequent short intensely hot flame, which flame terminates short of the screen 15 under normal operating conditions.

The water walls of the furnace shaped 20 boiler being subject to radiant heat, transmit heat at a very high rate indeed, in consequence of which there is not only a very rapid circulation through the tubes of the water walls, but also a very rapid circulation 25 through the standard boiler at the rear of the combustion chamber. Hence, the capacity 30 of the installation is greatly increased, and this with the addition of a relatively small combustion chamber of very simple construction. Furthermore, the relation between the 35 rate of fuel being fed under normal conditions and the volume of the combustion chamber, i. e., the amount of evaporating surface, is such that the gases leave the lower portion of the combustion chamber at a very 40 high temperature by virtue of which it is desirable to locate the superheater elements 26 in the off-take with the preheater means (not shown) located beyond the standard 45 boiler. By virtue of the high degree of heat of the gases leaving the combustion space, the standard boiler becomes an unusually effective economizer section.

Referring now to the arrangement shown 45 in Fig. 2, it will be seen that the same general type of furnace shaped tubular boiler, combustion chamber is provided in front of part of the boiler setting. In this case, however, a downcomer or downcomers 22^a 50 lead from the rear headers 27 of the horizontal tubular boiler C and upcomers 28 lead from the drum 18 to the headers 29 of the boiler. In all other essential respects the 55 installation and its operation is the same as that previously described.

Referring to Fig. 3, I have illustrated the application of the tubular combustion chamber described in front of a Sterling boiler.

60 Referring now to Fig. 4, I have herein illustrated an installation very much like that shown in Fig. 2. In this case, however, there are downcomer means 35 leading from the drum 36 to the drum 19, and there are upcomer means 37 leading from the drum 18

to the drum 36. Also, the tubes of the water screen 15^a are curved as shown to provide an outlet from the combustion chamber B² cooperating effectively with the outlet 38 leading to the off-take 39, as will be readily understood from inspection of the figures.

70 Other advantages will occur to those skilled in the art.

I claim:—

1. The combination with a boiler having a 75 bank of convection tubes and its setting, of a combustion chamber having its walls largely defined by steam generating tubes subject to radiant heat, the tubes of at least one of said walls being upright and provided with longitudinally extending fins, a gas space between the combustion chamber and the boiler, said gas space being defined in part by convection tubes of the boiler and in part by finned upright tubes of the combustion chamber, a gas inlet for said gas space establishing communication between the combustion chamber and the gas space and a gas outlet for said gas space establishing communication 80 between it and the boiler.

2. In combination, a combustion chamber 85 having walls thereof defined by upright steam evaporating tubes, a bank of upright convection tubes spaced from one of said upright walls of the combustion chamber, tubes of said bank forming with the tubes of said upright wall an upright passage through which gases leaving the combustion chamber must pass before passing amongst the tubes of the convection bank, and a superheater located in said passage.

3. In combination, a combustion chamber 90 having its upright walls defined by steam evaporating tubes and having an outlet for the products of combustion across which spaced evaporating tubes extend, a bank of convection tubes spaced from said combustion chamber and defining with an upright tubular wall of the combustion chamber an 95 upright gas passage having communication with said outlet, baffle means associated with said bank of tubes for providing a plurality of gas passes amongst the tubes of the bank and providing communication between said passes and said gas passage.

4. The combination with a bank of 100 convection boiler tubes, of a combustion chamber located to one side of said bank, a gas space between the combustion chamber and the bank of convection boiler tubes, boiler tubes 105 in said chamber largely defining the combustion space thereof including upright boiler tubes constituting a dividing wall between the combustion chamber and the gas space, said combustion chamber having an outlet communicating with one end of the gas space, and said gas space having an outlet at its other end for the passage of the gases of combustion 110 from the gas space to the bank of convection boiler tubes, and means for intro- 115

ducing fuel into the combustion chamber to be burned in space therein.

5. The combination with a bank of convection boiler tubes, of a combustion chamber located to one side of said bank, a gas space between the combustion chamber and the bank of convection boiler tubes, boiler tubes in said chamber largely defining the combustion space thereof including upright boiler tubes constituting a dividing wall between the combustion chamber and the gas space, said combustion chamber having an outlet in its lower portion communicating with the gas space at its lower portion, and said gas space having an outlet at its upper portion through which gases may pass to the bank of convection boiler tubes, and means for introducing fuel into the combustion chamber to be burned in space therein.

10 6. The combination with a bank of convection boiler tubes, of a combustion chamber located to one side of said bank, a gas space between the combustion chamber and the bank of convection boiler tubes, boiler tubes in said chamber largely defining the combustion space thereof including upright boiler tubes constituting a dividing wall between the combustion chamber and the gas space, said combustion chamber having an outlet in its lower portion communicating with the gas space at its lower portion, and said gas space having an outlet at its upper portion through which gases may pass to the bank of convection boiler tubes, and means for intro-

15 35 ducing fuel into the combustion chamber to be burned in space thereon, together with a superheater located in said gas space.

7. The combination with a furnace shaped tubular boiler having an upper drum to which the tubes of the boiler are connected, substantially all of said tubes being exposed to radiant heat, of a bank of convection tubes, an upper drum to which the upper ends of said convection tubes are connected, means connecting said first drum with said latter drum and means connecting the lower ends of the said convection tubes to the tubes of the furnace shaped boiler.

8. The combination with a furnace shaped tubular boiler having an upper drum to which the tubes of the boiler are connected, substantially all of said tubes being exposed to radiant heat, of a bank of convection tubes, an upper drum to which the upper ends of said convection tubes are connected, means connecting said first drum with said latter drum and means connecting the lower ends of said convection tubes to the tubes of the furnace shaped boiler, the said convection tubes constituting the sole downcomer for the boiler.

9. The combination with a furnace shaped tubular boiler having an upper drum to which the tubes of the boiler are connected, substantially all of said tubes being exposed to radi-

ant heat, of a bank of convection tubes, an upper drum to which the upper ends of said convection tubes are connected, means connecting said first drum with said latter drum comprising a plurality of substantially horizontal tubes, and means connecting the lower ends of the said convection tubes to the tubes of the furnace shaped boiler.

10. In combination a furnace shaped boiler the side walls of the combustion chamber thereof including rows of substantially upright tubes subject to radiant heat, means connecting the upper ends of said rows of tubes to a common drum, a bank of convection tubes, an upper drum to which the upper ends of said convection tubes are connected, means connecting said first drum with said latter drum and means connecting the lower ends of the said convection tubes to the tubes of the furnace shaped boiler.

11. In combination a furnace shaped boiler the side walls of the combustion chamber thereof including rows of substantially upright tubes subject to radiant heat, a drum at the upper end of one of said rows of tubes and headers at the upper ends of the other rows of tubes, said headers being connected to said drum, a bank of convection tubes, an upper drum to which the upper ends of said convection tubes are connected, means connecting said first drum with said latter drum and means connecting the lower ends of said convection tubes to the tubes of the furnace shaped boiler.

In testimony whereof, I have hereunto signed my name.

JOHN VAN BRUNT.
